UNITED STATES PATENT OFFICE

TALMA T. GREENWOOD, OF EAST TEMPLETON, MASSACHUSETTS, ASSIGNOR TO CONDUIT ELECTRICAL MANUFACTURING CORPORATION, OF SOUTH BOSTON, MASSACHUSETTS, A CORPORATION OF MASSACHUSETTS

ELECTRIC SWITCH AND ARC EXTINGUISHING METHOD

Application filed December 1, 1926, Serial No. 152,049. Renewed January 21, 1930.

This invention relates to electric switches and has for an object the provision of electrostatic means to extinguish the circuit interrupting arc combined with means providing a pressure chamber in which the circuit interrupting arc is drawn.

A further object of the invention is generally to improve the construction and operation of electric switches.

10 The idea of extinguishing a circuit interrupting arc by an electrostatic field is disclosed in my co-pending application Serial No. 152,048, filed December 1, 1926.

15 Fig. 1 is a sectional elevation taken through an electric switch embodying the invention.

Fig. 2 is an enlarged sectional elevation taken through the arc extinguishing chamber carried by one of the switch terminals.

20 Fig. 3 is a diagrammatic representation of the electric circuits of the invention.

The electric switch embodying this invention comprises an enclosing casing 10 adapted to be filled with some suitable arc quenching and electrically insulating liquid as oil to some level 12. Switch terminals comprising conducting studs 14 and insulators 16 for said studs are carried by the cover 18 of said casing and depend into the oil therein. Each stationary switch member is provided with a stationary arcing member and pressure chamber and means to establish an electrostatic arc-extinguishing field in the vicinity of the arcing member. The parts 25 associated with but one switch terminal need be described.

An attaching plate 20 is secured by a nut 22 to the lower end of the switch terminal and is electrically connected with the stud 14 thereof. Said plate is provided with one or more depending arms 24 which are integral with a substantially horizontal disc-shaped plate 26. Said plate is provided with an internally screw-threaded aperture in the middle thereof in which an upstanding bushing 28 is screw-threaded. The open upper end of said bushing has a cap 30 removably connected therewith. A segmental tubular contact or arcing member 32 is disposed beneath said cap 30 and the segments

thereof are connected to said cap by spring members 34. A metal bowl 36 surrounds said plate 26 and said arcing member and forms a strong pressure-retaining chamber in which the circuit interrupting arc is 45 adapted to be drawn. Said bowl 36 is provided with an integral bottom wall 38 having an opening 40 in the bottom thereof. A bowl-shaped insulating member having the cylindrical side wall 42 and bottom wall 44 is received within said metal bowl 36 and forms an insulating lining therefor in which the circuit interrupting arc is adapted to be drawn. The bottom wall of said insulating bowl is provided with an aperture 46 through which the movable contact or arcing member is adapted to be passed.

Said metal bowl is adapted to be secured rigidly to and electrically insulated from said plate 26. To this end a plate of insulating material 48 is disposed on the top plate 26 and a metal clamping ring 50 is internally screw-threaded engagement with the upper end of said bowl 36 whereby to clamp said bowl to said plate 26 through the 75 medium of said insulating plate 48 and said insulating bowl 42.

The movable switch member comprises a switch operating rod 52 which carries a horizontally disposed conducting bar 54 at its 80 lower end. Movable contact or arcing members 56 comprising vertically extended cylindrical rods are secured to the ends of said bars 54 in position to enter the apertures 56 in the bottom walls of the pressure chambers and make contact with the stationary contact members 32.

In accordance with this invention, said bowls 36 are utilized to set up an electrostatic field in the vicinity of the circuit interrupting arcs between said stationary and movable contact members whereby to extinguish the arcs. To this end, each switch terminal is provided with a current transformer 58 at its lower end which transformer is well known in the art and comprises an iron core, and a secondary winding, the primary comprising the stud of the switch terminal. One terminal 60 of the current transformer is connected with the attaching 100

- plate 20 and thereby electrically with the stationary contact member. The other terminal 62 of the secondary transformer is connected electrically with the insulated metal bowl 36 by means of the screw 64. The metal bowl therefor is adapted to be at a different potential than the arcing members. If, for instance, the stationary arcing member happens to be negative the connections of the transformer are so arranged that the bowl is made more negative than the arc member. Under this condition, the negative electrons in the arc stream will be repelled away from the movable contact member and the circuit interrupting arc will thereby be extinguished.

Pressure or explosion chambers per se are old in the art. These chambers, however, usually have been electrically connected with the stationary switch member by which they have been supported and so have not been adapted to make use of the principle herein set forth.

The pressure or explosion chamber serves to confine the gases and pressure that may result from the drawing of the arc and the electrostatic field of the chamber serves to extinguish the arc rapidly.

This invention in one aspect consists in insulating the explosion chamber from its associated contact member and electrifying said chamber at a potential which is different from the potential of said arcing member.

38. The construction may be otherwise modified without departing from the spirit of the invention.

I claim:

1. The method of interrupting an electric circuit which consists in drawing a circuit interrupting arc between separable contact members in a closely confined fluid body, and subjecting the circuit interrupting arc to the arc extinguishing action of an electrostatic field which is at a potential that is different from the arc potential.

2. The method of extinguishing a circuit interrupting arc which consists in subjecting the arc to the combined action of fluid pressure and an electrostatic field which is at a potential that is different from the arc potential.

3. The method of interrupting an electric circuit which consists in drawing a circuit interrupting arc between separable contact members in a closely confined fluid body, and simultaneously subjecting the circuit interrupting arc to the extinguishing action of fluid pressure and to an electrostatic field which is at a potential that is different from the arc potential.

4. The method of extinguishing an electric arc which consists in establishing the arc in a pressure resistant chamber which is also the source of an electrostatic field that is at a

potential that is different from the arc potential and which acts on the arc to extinguish it.

5. An electric switch having the combination of a pressure resistant chamber, contact members separable therein and means including said chamber providing an arc-extinguishing electrostatic field in the region including said arcing members.

6. An electric switch having the combination of a pressure resistant chamber, contact members separable therein, and means to electrify said chamber at a potential different from the potentials of said contact members.

7. An electric switch having the combination of a pressure resistant chamber having a metal wall, contact members separable therein, means to insulate said chamber from said contact members, and means to apply a potential to said chamber which is different from the potentials of said contact members.

8. An electric switch having the combination of a pressure resistant chamber having a metal wall, contact members separable therein, means to insulate said chamber from said contact members, and means to apply a potential to said chamber which is different from the potentials of said contact members, said means comprising a current transformer energized from the circuit of said contact members.

9. An electric switch having the combination of an insulated switch terminal, a stationary contact member carried at the lower end thereof, a conducting pressure resisting chamber surrounding said contact member and having insulating means connecting it mechanically with said switch terminal, a contact member movable in and out of said chamber in cooperative relation with the aforesaid contact member, and means to apply a potential to said chamber different from the potentials of said contact members.

10. An electric switch having the combination of an insulated switch terminal, a stationary contact member carried at the lower end thereof, a conducting pressure resisting chamber surrounding said contact member and having insulating means connecting it mechanically with said switch terminal, a contact member movable in and out of said chamber in cooperative relation with the aforesaid contact member, and means to apply a potential to said chamber different from the potentials of said contact members, said means including a current transformer carried by said switch terminal and having its winding connected to said switch terminal and also to said conducting chamber.

11. An electric switch having the combination of a switch member provided with a contact member, an insulated casing enclos-

- ing said switch member and having an opening therein, a movable contact member movable through said opening into and out of engagement with said first contact member, 5 said casing having a conducting part which surrounds said opening, and means to apply a potential that is different from the potentials of said contact members to said conducting part.
- 10 12. An electric switch having the combination of a switch member provided with a contact member, an insulated casing enclosing said switch member and having an opening therein, a movable contact member movable through said opening into and out of engagement with said first contact member, 15 said casing having a conducting part which surrounds said opening, and means to apply a potential that is different from the potentials of said contact members to said conducting part, said means including a transformer which is energized from said switch circuit.
12. An electric switch having the combination of a switch member provided with a contact member, an insulated casing enclosing said switch member and having an opening therein, a movable contact member movable through said opening into and out of engagement with said first contact member, 20 said casing having a conducting part which surrounds said opening, and means to apply a potential that is different from the potentials of said contact members to said conducting part, said means including a transformer which is energized from said switch circuit.
- 25 13. An electric switch having the combination of a switch member provided with a contact member, an insulated casing enclosing said switch member and having an opening therein, a movable contact member movable through said opening into and out of engagement with said first contact member, 25 said casing having a conducting part which surrounds said opening, and means to apply a potential that is different from the potentials of said contact members to said conducting part, said means including a transformer which is energized from said switch circuit and has a connection with said first contact member and another connection with said conducting part.
- 30 14. An electric switch having the combination of a switch member provided with a contact member, an insulated casing enclosing said switch member and having an opening therein, a movable contact member movable through said opening into and out of engagement with said first contact member, 30 said casing having a conducting part which surrounds said opening, and means to apply a potential that is different from the potentials of said contact members to said conducting part, said means including a current transformer which has a primary in series with the switch circuit and a secondary which is connected between said first contact member and said conducting part.
- 35 15. An electric switch having the combination of a switch member provided with a contact member, an insulated casing enclosing said switch member and having an opening therein, a movable contact member movable through said opening into and out of engagement with said first contact member, 35 said casing having a conducting part which surrounds said opening, and means to apply a potential that is different from the potentials of said contact members to said conducting part, said means including a current transformer which surrounds and is carried by said switch member and has a secondary which is connected between the first contact member and said conducting part.
- 40 16. An electric oil switch having separable oil-immersed contact members between which an arc is drawn when said members are separated under load, and electrically-energized arc-extinguishing means which is at an electrostatic ion controlling electric potential surrounding one of said contact members and located adjacent the zone of the arc in position to act thereon and to effect the extinguishment of the arc and the interruption of the circuit.
- 45 17. An electric switch having separable contact members between which an arc is drawn, and electrically energized means which is at an ion controlling electric potential and which surrounds one of said contact members and is located adjacent the zone of the arc in position to act thereon and effect the extinguishment of the arc and the interruption of the circuit.
- 50 18. An electric switch having separable contact members between which an arc is drawn, means which is at an electric potential that is different from the potential of said contact members and which surrounds one of said contact members and is located adjacent the zone of the arc in position to act thereon and effect the extinguishment of the arc and the interruption of the circuit, and means to apply a potential to said first means, which potential is derived from the switch circuit.

CERTIFICATE OF CORRECTION.

Patent No. 1,825,228.

Granted September 29, 1931, to

TALMA T. GREENWOOD.

It is hereby certified that the name of the assignee in the above numbered patent was erroneously written and printed as "Conduit Electrical Manufacturing Corporation", whereas said name should have been written and printed as Condit Electrical Manufacturing Corporation, as shown by the records of assignments in this office; and that the said Letters Patent should be read with this correction therein that the same may conform to the record of the case in the Patent Office.

Signed and sealed this 17th day of November, A. D. 1931.

**M. J. Moore,
Acting Commissioner of Patents.**
